UNITED STATES PATENT OFFICE

2,249,303

INTERNAL MOTOR CLEANER

William R. Smith, Medicine Park, Okla.

Application July 5, 1940, Serial No. 344,167

1 Claim. (Cl. 184—1.5)

This invention aims to provide novel means for cleaning the parts of an internal combustion engine which are disposed within the crankcase.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in elevation, a device constructed in accordance with the invention, parts being in section;

Fig. 2 is an elevation wherein the structure is viewed at right angles to the showing of Fig. 1;

Fig. 3 is a transverse section on the line 3—3 of Fig. 2;

Fig. 4 is a sectional view illustrating the nozzle structure and attendant parts;

Fig. 5 is a top plan showing the pressure gauge and parts adjacent thereto;

Fig. 6 is a sectional view illustrating the hook-up when it is desired to drain the crankcase.

In carrying out the invention, there is provided a receptacle 1 for surplus cleaning fluid. On the bottom of the receptacle 1 is mounted, detachably and removably, a receiver 2 constituting a base for parts carried by it and hereinafter described. The receptacle 1 and the receiver 2 may be heated, if desired, by any suitable means indicated at 3 and forming no part of the present invention.

A vertical standard 4 is secured to the receiver 2 and is provided, near its lower end, with a transverse bracket 5 to which a depending gear pump 6 is attached, the gear pump being spaced from the bottom of the receiver 2. The vertical shaft of the gear pump 6 is marked by the numeral 7. The shaft 7 is journaled for rotation in vertically spaced bearing arms 8, projecting inwardly from the standard 4.

The standard 4 is provided at its upper end and slightly below its upper end with transverse rails 9, secured to the base pieces 10 of an electric motor 11, the shaft of the motor being vertically disposed, and being connected to the shaft 7 of

the pump 6 by a coupling 12. The bearings 8 carry the shaft 7.

The lower end of a discharge conduit 14 is connected to the pump 6, the discharge conduit extending upwardly and laterally. By means of a coupling 15, the upper end of the discharge conduit 14 is connected to a hand valve 16. The hand valve 16 is connected to a plug 17, carrying a screen 18.

The crankcase of an internal combustion engine is marked by the numeral 19. The ordinary drain plug (not shown) of the crankcase is removed, and in its place, the plug 17 is threaded into the crankcase.

A hand valve 20 is interposed in the discharge conduit 14. The hand valve 20 is joined by a connection 21 to a pressure gauge 22 carried by the motor 11.

A depending by-pass pipe 23 is connected to the valve 20 and extends downwardly into the receiver 2.

The motor 11 drives the pump shaft 7, the pump 6 is operated, the pump takes cleaning fluid from the receiver 2, and the cleaning fluid is discharged through the conduit 14 and through the screen 18 into the crankcase 19, parts within the crankcase being cleaned by spray proceeding through the screen. The flow through the screen 18 is under the control of the hand valve 16.

The gauge 22, being connected to the discharge conduit 14 by way of the valve 20, shows the pressure that has been attained in the conduit 14. The pressure in the conduit 14 may be regulated by so manipulating the valve 20 that some of the cleaning liquid will by-pass through the pipe 23, into the receiver 2.

The receptacle 1 serves to hold cleaning fluid that may spill out of the receiver 2. Moreover, if desired, the cleaning fluid may be disposed at any desired height, within the receptacle 1, the receiver 2, of course, being kept full also.

The plug 17 may be detached from the crankcase 19, so that cleaning fluid can drain out of the crankcase. The coupling 15 may be disassociated from the hand valve 16. Then, as shown in Fig. 6, the coupling 15 may be assembled with a nipple 24, which, in its turn, is joined to any desired part 25 of the pressure gauge line on the motor. In this way, the cleaning fluid will be discharged back through the main bearings of the crankshaft, the connecting rods, the piston pins and the cylinder wall, the drainage taking place through the part of the crankcase shown in Fig. 4, it being recalled that the plug 17 of that

55 figure has been removed.

Having thus described the invention, what is claimed is:

A cleaner for internal combustion engines and the like, comprising a receptacle affording a substantial supporting base, a motor disposed above the base, a standard retaining the motor in centralized relation to the base and having its lower end secured to the receptacle, a pump, a shaft connection between the motor and the pump, and outlet means for the pump: the cleaner being

characterized by features which combine portability with a stable support by means of the base, in that the tank is shallow, provided with a top overflow, and of so limited a capacity that the tank and its maximum load will add a negligible weight-increment, the pump being disposed close to the bottom of the tank, and means independent of the shaft connection for supporting the pump in the position specified.

WILLIAM R. SMITH.
